BULK MATERIAL SQUEEZER

Lewis Miller, Marion, Ohio

Application October 27, 1942, Serial No. 463,563

1 Claim. (Cl. 100—31)

My invention relates to the tying of bulk material in shocks, bundles and the like, and has among its objects and advantages the provision of an improved fodder squeezer.

In the accompanying drawing:

Figure 1 is a side view of the fodder squeezer in its rope-tightening position;

Figure 2 is a similar view illustrating the rope latched to the fodder squeezer;

Figure 3 is a view illustrating the manner in which the binding string is manipulated;

Figure 4 is an edge view;

Figure 5 is an enlarged face view of the string holder and cutting blade; and

Figure 6 is an end view of the structure of Figure 5.

In the embodiment selected for illustration, I make use of a bar 10 having a grooved wheel 12 rotatably connected therewith near one end of the bar. A rope-latching bar 14 is pivotally connected intermediate its ends with the bar 10 to pivot in the plane of wheel 12. To the bar 10 is fixedly secured a string holder and cutting blade 16. A bolt 18 pivotally connects the latch bar 14 with the bar 10 and secures the blade 16 to the bar. This blade is provided with a flange 20 engaging one edge of the bar 10 to be restrained from rotation. One edge of the blade 16 is provided with a cutting edge 22 of slightly curved contour. A slot 24 is provided in the blade 16 for the reception of a tying string. This slot is widened at 26 to facilitate insertion of the string. This slot is relatively narrow so as to have firm binding engagement with the string when the latter is pulled into place. The slot 24 substantially parallels the cutting edge 22.

In operation, one end of a tightening rope 28 is threaded through an opening 30 in one end of the latch bar 14 and made secure, as by knotting. The device is thrown into the shock and the rope 28 is carried around the shock and then placed in the grooved wheel 12, as in Figure 1. A pull is then exerted on the rope 28 to tightly compact the shock or other bulk material, after which the latch bar 14 is brought to the position of Figure 2 to have end engagement with the rope 28 and latch the latter firmly to the wheel 12. Such engagement between the latch bar 14 and the rope 28 restrains the wheel 12 from rotation, so that the shock or other bulk material will be supported in its compacted condition by reason of the rope 28.

One end of a tying string 32 is then pulled

into the slot 24 and the string is carried around the shock and cut for length through the medium of the edge 22. After cutting for length, the binding string is tied and the rope 28 removed from the bundle.

The blade 16 serves a twofold function in that it constitutes an anchor for one end of the tying string, in addition to its knife function. This greatly facilitates handling of the tying string in that the work may be done in an expeditious manner by one person. In the past, it has frequently been necessary for two persons to cooperate in the tying action, one holding the tying string while the other walked around the shock to loop the tying string thereabout. The string is easily pulled into the slot 24 and is held sufficiently firm thereby to retain the string while looping it about the shock. The cutting edge is located in close proximity to the slot so that the tying string may be accurately cut for length to eliminate waste, and the two ends of the string are brought into close relationship so as to facilitate tying.

Without further elaboration, the foregoing will so fully illustrate my invention, that others may, by applying current knowledge, readily adapt the same for use under various conditions of service.

I claim:

A shock compressing and tying device, comprising an elongated bar-shaped body carrying a pulley to receive the binding line, a bar pivotally mounted on one side of the body for connection with one end of the binding line and swingable to a clamping position with respect to the line on the pulley, a flat plate-like member carried on the body opposite the bar and provided with a right angular lateral flange along one edge extending across the edge of the body, a bolt extending through the plate member, the body, and the bar to attach the bar and the plate member to the body, said flange preventing rotational movement of the plate member with respect to the body, the part of the plate member opposite the flange projecting below the body and shaped to curve forwardly toward the pulley, the curved edge adjacent the pulley being sharpened to provide a knife edge, and the plate formed with a tying string receiving slot spaced from and inclined and substantially parallel with the knife edge and having a wide mouth to facilitate insertion of the string.

LEWIS MILLER.
